UNITED STATES PATENT OFFICE.

ANTHONY M. LAUB, OF CRESO, IOWA.

WASHING APPARATUS.

1,254,815.

Specification of Letters Patent. Patented Jan. 29, 1918.

Application filed June 30, 1917. Serial No. 177,902.

To all whom it may concern:

Be it known that I, ANTHONY M. LAUB, a citizen of the United States, residing at Cresco, in the county of Howard and State 5 of Iowa, have invented certain new and useful Improvements in Washing Apparatus, of which the following is a specification, reference being had to the accompanying drawings.

10 This invention relates to certain improvements in washing apparatus and has relation more particularly to a device of this general character, especially designed and adapted for use in connection with dishes and kindred articles and it is an object of 15 the invention to provide a device of this general character having novel and improved means whereby dishes or the like may be thoroughly cleansed with convenience and facility.

It is also an object of the invention to provide a novel and improved washing apparatus of this general character including an article carrier mounted for rotary movement together with means for intermittently rotating said carrier and wherein a rotatable cleaning brush is movable with the carrier and co-acting with the article carried thereby.

30 A further object of the invention is to provide a washing apparatus including a novel and improved cleaning member which automatically adjusts itself to conform to a face of the article to be cleansed and which 35 also serves to automatically eject or discharge the article with which it co-acts at a predetermined period.

A still further object of the invention is to provide a novel and improved apparatus 40 whereby the outer and inner faces of the article to be cleansed are effectively engaged by suitable members or brushes.

The invention consists in the details of construction and in the combination and 45 arrangement of the several parts of my improved washing apparatus wherein certain important advantages are attained and the device rendered simpler, less expensive and otherwise more convenient and advantageous for use, as will be hereinafter more fully set forth.

The novel features of the invention will hereinafter be definitely claimed.

In order that my invention may be the 55 better understood I will now proceed to

describe the same with reference to the accompanying drawings, wherein:

Figure 1 is a view in top plan with certain of the parts in section of a washing apparatus constructed in accordance with an 60 embodiment of my invention;

Fig. 2 is a sectional view taken substantially on the line 2—2 of Fig. 1;

Fig. 3 is a fragmentary longitudinal vertical sectional view looking in the direction 65 opposite to what is shown in Fig. 2;

Fig. 4 is a fragmentary view partly in elevation and partly in section illustrating the operating means for the rocking brushes or members as herein included;

Fig. 5 is a fragmentary view in elevation 70 of the rocking brushes as herein included together with the mounting therefor;

Fig. 6 is an enlarged fragmentary view 75 partly in section and partly in top plan illustrating one of the holding members as herein included:

Fig. 7 is an enlarged view partly in section and partly in elevation illustrating a second holding member as herein included, 80 a co-acting arm being shown operatively engaged with said holding member;

Fig. 8 is an enlarged fragmentary view 85 partly in section and partly in end elevation illustrating certain details of the carrying arm and parts co-acting therewith as herein set forth;

Fig. 9 is a view in elevation of one of the rotating brushes as herein embodied;

Fig. 10 is an outer end view of the device 90 as disclosed in Fig. 9 with the fibers or brush member removed;

Fig. 11 is a fragmentary view in elevation 95 illustrating the means as herein disclosed for adjusting the carriers as herein included;

Fig. 12 is a fragmentary view partly in section and partly in elevation illustrating in detail the locking means as included in the structure illustrated in Fig. 11;

Fig. 13 is a view in end elevation of a bridge member herein employed;

Fig. 14 is a view in top plan of the bridge as illustrated in Fig. 13;

Fig. 15 is a fragmentary view illustrating 105 a side elevation of a rotating brush constructed in accordance with a further embodiment of my invention;

Fig. 16 is a view in end elevation of the brush as disclosed in Fig. 15;

Fig. 17 is a fragmentary view in top plan of the discharging end of my improved apparatus;

Fig. 18 is a view in side elevation of the structure as disclosed in Fig. 17; and

Fig. 19 is a longitudinal sectional view taken through Fig. 18.

As disclosed in the accompanying drawings T denotes a tub of predetermined dimensions and preferably semi-circular in a vertical plane and which has operatively engaged therewith the supporting legs L. The lower portion of the tub T is provided with the depending well W provided at substantially its center with a drain cock D. Co-acting with the upper or open face of the tub T is the cover C also substantially semi-circular in a vertical plane so that when the cover is in an applied position upon the tub a substantially cylindrical housing is afforded.

The free margins of the tub T and the cover C are provided with recesses adapted to register to afford an entrance opening to 25 E and a discharge opening O as is believed to be clearly illustrated in Fig. 2 of the accompanying drawings.

Extending outwardly from the tub T adjacent the discharge opening O is the rinsing box R adapted to contain hot water. Supported by the upper portion of the box R and immediately adjacent the discharge opening O is an endless apron A which is adapted to discharge upon the basket B supported by the upper longitudinal margins of the outer portion of the box R.

The apron A is disposed around the rollers 1 and one of said rollers has its shaft 2 extended beyond a side of the box R. Secured to the extended portion of the shaft 2 is a sprocket wheel 3 around which is disposed a sprocket chain 4 which is also directed around a sprocket 5 fixed to the shaft 6. The shaft 6 is rotatably supported by a side wall of the tub T and an outstanding bracket 7 carried by said side wall. The outer end of the shaft 6 is provided with any suitable operating means and as is particularly illustrated in Fig. 1 said operative means comprises a crank 8 to afford means whereby my improved apparatus may be manually operated. It is to be understood however that my improved device may be motor driven if preferred. Disposed transversely of the tub T at the axial center thereof is a shaft 9 which extends beyond opposite sides of the tub T and one extended portion thereof is provided with a gear 10 in mesh with a gear 10a fixed to the shaft 6 hereinbefore referred to.

Suitably fixed to the shaft 9 and positioned substantially at the transverse center of the tub T is the beveled gear G of predetermined diameter which is in mesh with

the gears 11 carried by the inner end portions of the shafts 12 radiating from the shaft 9. Each of the shafts 12 is rotatably disposed through the sleeve 14 interposed in a cross arm 15 connecting a parallel pair of arms 16 radiating from the hubs 17 loosely mounted upon the shaft 9 adjacent the opposite side walls of the tub T. During the operation of my improved apparatus the shafts 12 are continuously rotated.

Each of the shafts 12 is provided with an open bar or socket 18 extending longitudinally thereof and in which extends an end portion of a stem 19. The stem 19 is keyed to the shaft 12 through the medium of a pin 20 extending through the inner end portion of said stem and the longitudinally disposed slots 21 formed in the shaft 12 at diametrically opposed parts. Interposed between the inner end of the stem 19 and the base of the bar or socket 18 is an expansible member 22 herein disclosed as a conventional coil spring which serves to constantly urge the stem 19 outwardly.

Suitably fixed to the outer end portion of each of the stems 19 is a substantially U-shaped clip or bracket 23 which is intersected by the pin 24. 25 denotes two opposed backs having their inner or adjacent ends returned on a predetermined curvature as indicated at 26 and arranged side by side. The curved portions 26 are provided with the brackets 27 pivotally engaged with the pin 24 whereby it will be at once understood that the backs 25 are capable of swinging movement. The opposite ends of each of the backs 25 are provided with the notches 28 in which are sprung the extremities of the twisted wire strands 30. Held by the strands 30 are the outstanding 105 bristles 31. The bristles 31 are preferably hog bristles in order to effectively withstand hot water.

Loosely mounted upon each of the arms 19 inwardly of the bracket 23 is a sleeve 32 and pivotally engaged with said sleeve 32 at diametrically opposed parts are the rigid links 33 which have their outer ends pivotally engaged with the backs 25 at a predetermined point inwardly from the curved ends 26 thereof. It is thought to be self evident that as the stem 19 rotates the centrifugal action will result in the backs 25 moving outwardly so that the same will properly conform to the article with which it co-acts as will hereinafter be more fully set forth. The links 33 also assure that each of the backs 25 will move in unison.

Loosely mounted upon the shaft 9 inwardly of and immediately adjacent each of the hubs 16 is a pair of hubs 34 and radiating from said hubs are the rods 35. Each of the hubs 34 is provided with four equal distantly spaced rods 35 and the rods of one hub 34 are arranged in outward di-

vergence relative to the rods 35 of the hub of the same pair.

The rods 35 of a hub 34 of one pair are in parallelism with the rods 35 of a hub 34 of the second pair and each set of parallel rods has secured to the outer extremity thereof the transversely disposed plates 36. The opposed edges of the plates 36 co-acting with each set of rods 35 are provided with the recesses 37 to afford means whereby articles may be held between said plates 36, said articles being preferably hollow ware such as pitchers, cups or the like. It is to be understood that the plates 36 and their 10 co-operating parts serve as carriers and in order that said plates may effectively co-act with flat ware such as dining plates or the like I provide each of the plates 36 inwardly of the recess 37 with the outstanding 15 spring or resilient arms 38 provided with the offset portions 39 to afford means whereby a plate may be effectively grasped as is particularly illustrated in Fig. 2 of the accompanying drawings. It will also be understood that a plate can be grasped between the inner end portions of the arms 38 if preferred and the requirements of practice so necessitate.

In order that each pair of co-acting plates 36 may be relatively adjusted to compensate for the size of the articles to be cleansed I pivotally engage with adjacent rods 35 of one of the pairs of hubs 34 the links 40 which are also pivotally engaged with the sleeve 41 mounted for sliding movement upon an adjacent arm 16. The sleeve 41 is provided with a spring latch 42 engageable with the longitudinally spaced recesses 43 reduced in a face of the arm 16, as particularly illustrated in detail, Figs. 11 and 12, whereby the arms 35 and the plates 36 carried thereby may be effectively held in their different relative positions. It will also be at once understood that upon the adjustment 45 of a pair of arms 35 all of the pairs of arms 35 will be correspondingly adjusted. In order that the necessary access may be had within the tub or more particularly the cover C during a cleansing operation I provide the cover C with a door 44 as illustrated in Fig. 2.

An article to be cleansed is applied between a pair of plates 36 or arms 38 carried thereby through the entrance opening E and as the shaft 9 is rotated the centrifugal action will cause the backs 25 to swing upwardly to assure the requisite contact of the bristles 31 with the inner face of the article. The arms 16 together with the shafts 12 are 55 adapted to intermittently swing around the shaft 9 and are normally held against swinging movement through the medium of the stops 45 and 46, the stop 45 being positioned adjacent the entrance opening E and the stop 46 adjacent the discharge opening Q.

Opposed arms 16 at one side of the tub T rest upon said stops 45 and 46 whereby the arms 16 together with the shafts 12 are held against swinging movement relative to the shaft 9. Loosely mounted on the shaft 9 remote from the gear 10 is a large sprocket wheel 47 around which is disposed a sprocket chain 48 which is also directed around a sprocket wheel 49 positioned in advance of the shaft 9 and fixed to a shaft 50 extending outwardly of the tub T through the adjacent wall thereof. The outer end of the shaft 50 is operatively engaged through the medium of the sprocket chain 51 with the shaft 9 whereby it will be perceived that the sprocket 47 will be rotated around the shaft 9. The operative connections between the shaft 9 and the sprocket wheel 47 is such as to cause the sprocket 47 to make a complete rotation upon fourteen revolutions of the gear 11 so that each pair of parallel arms 16 or a shaft 12 will make a one-quarter turn upon three revolutions of the gear 11, or one revolution of the crank 8 on the one-quarter turn, or three and three-quarter revolution on a complete rotation of the sprocket 47. In other words the gear 11 makes fourteen revolutions to one complete rotation of the sprocket 47, or again sprocket 47 makes a complete rotation upon three and three-quarter revolutions of the gear 10 or crank 8.

Radiating from the sprocket 47 is an arm 52 having secured to the outer end thereof and at right angles thereto a substantially diamond-shaped plate 53 which serves to adjust the stop 45 into an inoperative position so that the arm 16 engaged therewith may pass therebeyond. The plate 53 contacts directly with a laterally directed finger 54 extending laterally from the stop 45 and through a longitudinally disposed slot 55 formed in a wall of the cylinder 56 in which the stop 45 is slidably mounted. The stop 45 is normally maintained in an operative position through the medium of an expandable member 57 herein disclosed as a conventional coil spring interposed between the inner end of the cylinder 56 and the stop 45. The cylinder 56 is operatively engaged with a side wall of the tub T and extends inwardly of the tub a requisite distance as particularly illustrated in Fig. 1 of the accompanying drawings.

Secured to the arm 52 at a predetermined point inwardly of the plate 53 is an end portion of the arm 58 disposed at right angles to the arm 52 and which has pivotally engaged with its free extremity a second plate 59 which is disposed in a direction toward the arm 52 and terminates in an angular extension 60 overlying the arm 52 and extending a predetermined distance therebeyond so that the extension 60 may be caused to overlie a rod 16 and cause the same to swing

4 around the shaft 9. The arms 58 and 59 are normally maintained separated in order to arrange the extension 60 in an inoperative position through the medium of the expansible member 61 interposed between the arms 58 and 59 and surrounding a pin 62. The pin 62 is operatively engaged with the plate 59 and is loosely disposed through the plate 58 at a point immediately adjacent to the 10 arm 58 immediately adjacent the arm 52 so that when the arm 59 is forced inwardly toward the arm 58 to cause the extension 60 to overlie an arm 16 the free end portion of the pin 62 will underlie the arm 16 to assure 15 the arm 16 moving in unison with and at the same speed as the arm 52. The relative separating movement of the arms 58 and 59 is controlled by a second pin 63 operatively engaged with the arm 59 and loosely disposed 20 through the arm 58 and having its outer extremity provided with the engagement or head 64 co-acting with the arm 58 in a manner and for a purpose which is believed to be clearly apparent, to those skilled 25 in the art to which my invention pertains. Secured to the side wall of the tub T adjacent the arms 52 is an arcuate strip or track 65 extending from a point adjacent the upper or open face of the tub T proper and 30 terminating above the longitudinal center of the well W. As the plate 53 carried by the arm 52 engages the pin 54 of the stop 45 the arm 59 engages the strip or track 65 and is forced inwardly thereby so that the extension 35 60 and the pin 62 is operatively engaged with the arm 16. When the arm 52 passes the lower end of the strip or track 65 the arm 59 is automatically forced upwardly by the expansible member 61 to free the 40 arm 16 of the extension 60 and the pin 62. At this time the corresponding arm 16 rearwardly of the arm 16 just released is brought in contact with the extended stop 45 while the corresponding arm 16 immediately in 45 advance of the released or depending arm 16 is in engagement with the stop 46.

The stop 46 comprises a plate 66 hingedly connected at its lower end and which has its upper end portion provided with an inclined extension 67 terminating in a depending lip 68 adapted to overlie the upper portion of a vertical plate 69 suitably anchored to a block 70 carried by the adjacent side wall of the tub T. The plate 66 is 50 normally maintained at the limit of its extended movement by the spring member 71 interposed between the plates 66 and 69 as clearly illustrated in Fig. 7. Normally the inclination of the plate 66 is such as to 55 readily permit an arm 16 to pass upwardly thereby. The arm 16 and the shafts 12 are now held against swinging movement about the shaft 9 until the arm 52 has again operatively engaged the stop 45 whereby it will 60 be at once understood that the arms 16 and

their co-operating parts are intermittently swung or rotated about the shaft 9 in order to facilitate the cleansing operation of the articles carried by the plates 36.

When the arms 16 and their co-operating parts are brought to a stop it will be at once self-evident that the expansible member 22 of the cleansing brushes co-acting with the stem 19 at the discharge opening O will automatically deliver the article to the apron A and that said article will be carried by the apron A to the basket B. It is also to be understood that the tub T is adapted to be filled with hot water and that a suitable cleansing agent preferably of a saponaceous character may be dissolved with the water.

Pivotaly supported by the side walls of the tub T is a substantially U-shaped yoke Y which has its base portion extended within the well W and pivotally supported by the side arms 72 adjacent the lower or intermediate portion 73 thereof is a cradle 74. Rotatably supported by the cradle 74 is a plurality of brushes 75 extending transversely of the tub T and preferably arranged in arcuate relation. The brushes 75 are adapted to co-act with the bottoms or outer faces of the articles and thereby further facilitate the cleansing thereof. The yoke Y is adapted to be rocked to further assure the cleansing action of the brushes 75 and as herein embodied one of the side arms 72 is provided above its pivot 76 with an angular extension 77. The extension 77 is provided with a longitudinally disposed slot 78 through which is directed a pin 79 carried by an arm 80. The arm 80 is suitably fixed to the shaft 6 hereinbefore referred to.

I also found it of advantage to provide the bottom wall of the tub T with parallel track ways 81 with which the articles to be cleansed contact and which serve to facilitate the travel of the articles within the tub. I also found it of advantage to seat within the well W the bridge member M which includes the end plates 82 adapted to abut the wall of the well W. The plates 82 are connected by the arcuate tracks 83 adapted to register with the trackways 81 so that the dropping of the articles being cleansed within the well W is prevented. The bridge member M may be held within the well W in any desired manner but as is particularly illustrated in Fig. 3 the member M is maintained within the well W through the medium of the clips 84 overlying the end plates 82 of the bridge member M.

I also found it of advantage to connect the end plates 82 of the bridge member M at one side thereof with the rod 85 and which rod 85 serves to guide the cradle 74 in its movements. I also found it of advantage to interpose between the inner end portion of the rinsing box R and the tub T

the draining pipe 86 in which is interposed a controlling valve 87. It will be at once self evident that when desired the water within the box R may be drained into the 5 tub T and withdrawn from the tub T through the drain cock D.

As is particularly illustrated in the embodiment of my invention as disclosed by Figs. 15 and 16 of the accompanying drawings I find it of advantage to secure to each of the backs 25 the plates 88 arranged on a predetermined pitch so that as the brushes operate within the fluid contained in the tub T a stronger pressure is imposed upon the 15 articles to be cleansed.

Pivottally engaged with the opposite end portions of the shaft 2 are the longitudinally disposed bars 89 connected adjacent their opposite ends by the transversely 20 spaced rods 90. The free end portions of the rods 89 rotatably support the shaft 91 of the second or outer roller 1 and the terminals of said shaft 91 are adapted to engage the upper edges of the sides of the box R to 25 limit the downward swinging movement of the bars 89. In view of this construction it will be at once self evident that the apron A can be readily raised in order to permit access within the box R so that, if desired, 30 the dishes within the basket B may be thoroughly rinsed within the box R. I also find it of advantage to provide means for preventing the dishes delivered upon the apron A from falling back within the tub T. As 35 herein disclosed I accomplish this result through the medium of the arms 92 extending longitudinally of the apron A at the margins thereof and at the inner end of said apron. The outer ends of the arms 92 40 are continued by or integrally connected with the transverse rod 93 rotatably supported by the bars 89 whereby the arms 92 are capable of swinging movement in a vertical direction. The inner end portions of 45 the arms 92 are continued by the inwardly directed extensions 94 having their terminals rearwardly directed as at 95 and extending partially within the tub T through the discharge opening O. As the dishes are 50 brought up to the discharge opening R the arms 92 are raised upwardly by contact of said dishes with the terminals 95 so that no obstruction is offered to the discharge of the dishes upon the apron A. After a dish 55 has been discharged upon the apron A the arms 92 fall back upon the apron and the inwardly directed portions 94 of said arms serve to prevent the dish from falling back into the tub T through the opening O.

60 From the foregoing description, it is thought to be obvious that a washing apparatus constructed in accordance with my invention is particularly well adapted for use by reason of the convenience and facility 65 with which it may be assembled and oper-

ated and it will also be obvious that my invention is susceptible of some change and modification without materially departing from the appearance and spirit thereof and for this reason I do not wish to be understood as limiting myself to the precise arrangement and formation of the several parts herein shown in carrying out my invention in practice except as hereinafter claimed.

I claim:

1. In a washing apparatus, a tub, a plurality of carrying means supported for rotary movement and adapted to travel through the tub, means for intermittently 80 rotating said carrying means, a brushing means co-acting with each of the carrying means, said brushing means being supported for rotary movement and traveling with the carrying means, each of said carrying means 85 comprising two relatively movable members, and means for holding said relatively movable members against independent movement.

2. In a washing apparatus, a tub, a plurality of carrying means supported for rotary movement and adapted to travel through the tub, means for intermittently 90 rotating said carrying means, a brushing means co-acting with each of the carrying means, said brushing means being supported for rotary movement and traveling with the carrying means, each of said carrying means 95 comprising two relatively movable members, means for holding said relatively movable 100 members against independent movement, said holding means being also operable to adjust said relatively movable members toward or from each other.

3. A washing apparatus, comprising a 105 tub, a shaft intersecting said tub, a plurality of arms rotatably supported by the shaft and radiating therefrom, a cleansing means operatively engaged with each of the arms, means co-acting with the arms for holding 110 the same against movement around the shaft, and driven means co-acting with the arms for intermittently moving same about the shaft, said last named means also serving to disengage the holding means from 115 the arms.

4. A washing apparatus, comprising a 120 tub, a shaft intersecting said tub, a plurality of arms rotatably supported by the shaft and radiating therefrom, a cleansing means 125 operatively engaged with each of the arms, means co-acting with the arms for holding the same against movement around the shaft, driven means co-acting with the arms for intermittently moving same about the shaft, said last named means also serving to disengage the holding means from the arms, and means co-acting with the driven means for limiting the operative engagement of said driven means with an arm. 130

5. A washing apparatus, consisting of a tub, a plurality of radiating arms adapted to travel around a common center, article engaging means carried by each of the arms, a continuously driven member, an arm radiating from said last named member, an end-wise movable latch normally intersecting the path of travel of the first named arms, means carried by the arm of the driven member for forcing the latch out of the path of travel of the first named arms, and means carried by the arm of the driven member for engaging one of the first named arms for causing said first named arms to travel in unison with and in the same general direction as the last named arm for a predetermined distance.

6. A washing apparatus, comprising a tub, a plurality of radiating arms adapted to rotate in unison about a common center, a driven member, an arm radiating from said driven member, relatively movable arms carried by said last named arm, one of said relatively movable arms being provided with a lateral extension adapted to overlie one of the first named radiating arms to cause said radiating arms to travel in unison with the arm radiating from the driven member, automatic means for normally maintaining the angular portion of one of the relatively movable arms out of the line of travel of the radiating arms, and automatic means for maintaining the angular extension of one of the relatively movable arms in a position to overlie one of the first named radiating arms for a predetermined distance along the path of travel of the arm radiating from the driven member.

7. A washing apparatus, comprising a tub, a plurality of radiating arms adapted to rotate in unison about a common center, a driven member, an arm radiating from said driven member, relatively movable arms carried by said last named arm, one of said relatively movable arms being provided with a lateral extension adapted to overlie one of the first named radiating arms to cause said radiating arms to travel in unison with the arm radiating from the driven member, automatic means for normally maintaining the angular portion of one of the relatively mov-

able arms out of the line of travel of the radiating arms, automatic means for maintaining the angular extension of one of the relatively movable arms in a position to 55 overlie one of the first named radiating arms for a predetermined distance along the path of travel of the arm radiating from the driven member, and a pin carried by the relatively movable arm provided with an extension adapted to overlie a second face of one of the first named radiating arms when the extension of one of said relatively movable arms is operably engaged with one of said first named radiating arms. 65

8. A washing apparatus comprising a tub, a rinsing box positioned adjacent thereto, an endless apron supported by the rinsing box and positioned adjacent the tub, carriers traveling through the tub, brushing means 70 co-acting with the carriers, said brushing means serving to automatically eject an article upon the endless apron when the carriers position an article immediately adjacent said apron, and means for preventing 75 the return of the articles within the tub when ejected upon the endless apron.

9. A washing apparatus, comprising a tub, a rinsing box positioned adjacent thereto, an endless apron supported by the rinsing 80 box and positioned adjacent the tub, said endless apron being capable of swinging movement relatively to the rinsing box, carriers traveling through the tub, and brushing means co-acting with the carriers, said 85 brushing means serving to automatically eject an article upon the endless apron when the carriers position an article immediately adjacent said apron.

10. In a washing machine, a tub, carrying means traveling therethrough, a yoke positioned within the tub, and mounted for swinging movement, a cradle pivotally supported by the lower portion of the yoke, brushing means carried by the cradle, and 95 means for swinging the yoke.

In testimony whereof I hereunto affix my signature in the presence of two witnesses,

ANTHONY M. LAUB.

Witnesses:

E. P. FARNSWORTH,
E. L. WEAKLEN.
